UNITED STATES PATENT OFFICE

FRED CLARKE GLUCK, OF MINERVA, OHIO, ASSIGNOR TO THE COATED PAPER PRODUCTS COMPANY, OF MINERVA, OHIO, A CORPORATION OF OHIO

PAPER DISPENSING DEVICE

Application filed October 2, 1930. Serial No. 485,924.

This invention relates to dispensing cabinets for sheet material.

One object of this invention is to provide a simple and effective cabinet for holding 5 and dispensing sheet material such as paper.

Another object is to arrange the elements of the container in such a manner as to permit unobstructed access to the roll or package of paper therein for the purpose of with- 10 drawing the free end of the sheet. Other objects are to provide an improved arrangement for severing the paper and convenient means for loading the cabinet, to provide an improved roll or package of paper or other 15 sheet material, and to secure a novel combination of a cabinet and a sheet material roll whereby the roll is correctly positioned and tensioned within the cabinet to facilitate the dispensing and severing of sheets of any de- 20 sired size.

Other objects will appear in the following detailed description of a preferred embodiment of the invention.

In the accompanying drawing:

25 Fig. 1 is a front elevation of the improved cabinet, showing the same attached to a wall and with a roll of sheet material therein.

Fig. 2 is a section taken on the line 2—2 of Fig. 4.

30 Fig. 3 is a top plan view of the device.

Fig. 4 is a section taken on the line 4—4 of Fig. 1.

Referring to the drawing, the numeral 10 35 designates generally a dispensing cabinet constructed in accordance with this invention. The cabinet is preferably constructed of sheet metal, and includes a front wall 11 having integral end walls 12 extending rear- 40 wardly therefrom and terminating in mount- 45 ing ears or the like 13 adapted to receive screws 14, for supporting the cabinet on a wall or other surface.

The top of the cabinet is closed by means 45 of a cover 15 which may be wholly remov- 50 able or hinged to the side walls 12. In the embodiment illustrated, the rear edge of the cover is provided with laterally projecting lugs 16 which pivotally engage in apertures 17 formed in the side walls 12.

55 The rear side of the container is left open,

but is closed by the supporting surface when the cabinet is mounted thereon. The bottom is left completely open and unobstructed to allow access to the roll of material, and the lower edge 18 of the front wall 11 is designed 55 to form a cutting edge for severing pieces of the desired size from the roll.

Each of the end walls 12 is provided with an outwardly pressed recess 19 extending part way down the wall from the upper edge 60 thereof and terminating in an arcuate shoulder 20. The shoulders 20 are axially aligned and are arranged to support the roll 21 of sheet material.

The roll 21 is wound on a core 22 prefer- 65 ably formed of heavy cardboard or the like, or any suitable material which is capable of supporting and tensioning the roll. The core 22 is made longer than the width of the material constituting the roll 21, to provide 70 projections 23 at each end of the roll adapted to fit in the recesses 19 and engage the arcuate shoulders 20 to support the roll.

In order to properly position the roll, the 75 diameters of the core 22 and the arcuate shoulders 20 are substantially equal so that the external surfaces of the projections 23 engage the shoulders 20 throughout a long arc. In order to tension the roll sufficiently to permit the end of the sheet being drawn 80 against the cutting edge 18 and severed, the projections 23 of the core are made of relatively large diameter preferably more than half the diameter of the roll, to provide a relatively long radius through which the 85 friction between the projecting ends 23 and the shoulders 20 acts to resist rotation of the roll 21.

After the cabinet is secured to a support- 90 ing surface, a roll of sheet material may be placed therein by raising the cover 15, placing the projecting ends 23 of a roll in the open ends of the recesses 19, and moving the same downwardly through the recesses 95 into engagement with the arcuate shoulders 20. The roll is positioned with the free end of the sheet passing downwardly between the roll and the front wall 11 of the cabinet, as shown in Fig. 4. To start the free end 100 of the roll in the event the same should

be initially positioned in an inaccessible position, or should become displaced during use, it is only necessary to reach upwardly through the open bottom and turn 5 the roll until the end of the sheet may be grasped. The open bottom also facilitates separating the free end from the roll if it should adhere thereto for any reason.

The sheet may then be withdrawn until 10 a piece of the desired size has been exposed below the cutting edge 18, the friction between the projecting ends 23 and the shoulders 20 permitting rapid withdrawing of the sheet without danger of the roll over-running, and exposing a greater quantity of 15 material than desired. The sheet is then drawn upwardly against the edge 18 and severed, the frictional resistance of the bearings holding the roll against rotation with 20 sufficient force to permit a straight cut across the width of the sheet.

Although the foregoing description is necessarily of a detailed character in order 25 that the invention may be fully disclosed, it is to be understood that various rearrangements of parts and modifications of detail, may be resorted to without departing from the spirit and scope of the invention as defined in the following claims.

30 I claim:

1. A dispensing cabinet comprising a front wall having opposed end walls integral therewith, means for mounting the cabinet on a support, means associated with said end walls for supporting a roll of sheet material, and a cutting edge at the lower side of said 35 front wall for severing sheet material from the roll, the bottom of the cabinet being substantially unobstructed to permit access to 40 the roll.

2. A dispensing cabinet including a front wall and end walls, said end walls having upwardly opening recesses terminating in shoulders to receive and support a roll of 45 sheet material, a movable cover arranged to close the open ends of said recesses, and a cutting edge carried by said front wall, the bottom of the cabinet being substantially open to permit access to the roll.

50 3. In combination, a dispensing cabinet including a front wall, end walls, and a cover, said end walls having outwardly pressed recesses therein opening through the upper edges of the walls and terminating in 55 arcuate shoulders, the bottom of the cabinet being open, and a roll of sheet material having cylindrical bearings projecting from the ends thereof and frictionally engaging said shoulders, said bearings and shoulders being 60 designed to produce sufficient frictional resistance to rotation of said roll to properly tension the same and prevent overrunning of said roll.

65 4. In combination, a dispensing cabinet including a front wall, end walls, and a

cover, said end walls having outwardly pressed recesses therein opening through the upper edges of the walls and terminating in arcuate shoulders, the lower edge of the front wall constituting a cutting edge and the bottom of said cabinet being open, and a roll of sheet material wound upon a core longer than the roll and projecting beyond the ends thereof, the projecting ends of said core resting in said arcuate shoulders and frictionally engaging the same to support and tension said roll.

5. A dispensing cabinet for a roll of sheet material comprising a front wall having opposed end walls integral therewith, means for mounting the cabinet on a support, means associated with said end walls for supporting said roll of sheet material and for restricting free rotation of said roll, said front wall having a cutting edge at the bottom thereof, and the bottom of the cabinet being open to permit access to said roll.

6. A dispensing cabinet for a roll of sheet material comprising a front wall having opposed end walls integral therewith, means for mounting the cabinet on a support comprising attaching tabs integral with said end walls, means associated with said end walls for supporting said roll of sheet material, said front wall having a cutting edge at the bottom thereof, the bottom of the cabinet being open to permit access to said roll.

7. A dispensing cabinet for a roll of sheet material comprising a front wall having opposed end walls integral therewith, said end walls being apertured near the upper rear corners thereof, means for mounting the cabinet on a support, means associated with said end walls for supporting said roll of sheet material, said front wall having a cutting edge at the bottom thereof, the bottom of the cabinet being open to permit access to said roll, and a cover having laterally projecting bearing lugs journaled in the said apertures in said end walls.

In testimony whereof I hereunto affix my signature this 23d day of August, 1930.

FRED CLARKE GLUCK.
